CLAIM

The ornamental design for a header ring for a pumping system substantially as shown and described.

DESCRIPTION

FIG. 1 is a perspective view of a header ring; FIG. 2 is a front view of the header ring; FIG. 3 is a back view of the header ring; FIG. 4 is a right side view of the header ring; FIG. 5 is cross-section view of the header ring taken along line 5-5 from FIG. 2; and,

FIG. 6 is a detailed cross-sectional view of the header ring taken along line 6-6 from FIG. 5.

The broken lines shown on the drawings depict portions of the header ring for a pumping system that form no part of the claimed design. The dash dot dash broken lines of longer length encircling portions of the claimed design and illustrated in enlargement views form no part of the claimed design.
